UNITED STATES PATENT OFFICE.

FRANK W. MIX, OF NEW BRITAIN, CONNECTICUT, ASSIGNOR TO THE
CORBIN CABINET LOCK COMPANY, OF SAME PLACE.

PIANO-LOCK.

SPECIFICATION forming part of Letters Patent No. 295,270, dated March 18, 1884.

Application filed January 2, 1884. (No model.)

To all whom it may concern:

Be it known that I, FRANK W. MIX, a citizen of the United States, residing at New Britain, in the county of Hartford and State 5 of Connecticut, have invented certain new and useful Improvements in Locks, of which the following is a specification.

My invention relates to improvements in self-locking locks for desks and other furniture; and the objects of my improvement are to simplify the construction of the lock and to increase its strength and efficiency. I attain these objects by the construction illustrated in the accompanying drawings, in 15 which—

Figure 1 is a front elevation of my lock with the cap removed, and Fig. 2 is a vertical section of the complete lock on line $x-x$ of Fig. 1.

A designates the face-plate; B, the lock- 20 plate; C, the cap, and D the keeper. The swinging dogs or hooks $a-a$ are arranged in pairs upon the sides of the key-hole b , as shown, and are pressed upon by springs c with a constant tendency to throw the hooked ends d , Fig. 25 1, outward. Only one pair of these dogs is necessary; but greater security against picking is afforded by the employment of more than one pair placed one over the other, after the manner of several tumblers. Locks having such dogs are quite common. Instead, however, of making the hooked ends of these dogs the only part that projects through the stationary face-plate A, I place these dogs in a housing, which I term the "hollow bolt" E. 30 This bolt is made of a size to enter and properly fill the hole in the keeper D, and its corners should be beveled or rounded off a little, to facilitate the entry of the bolt within the keeper in closing the lid of the box or case to 35 which the lock is applied. The edges of the bolt are left open, so that the hooked ends d , Fig. 1, can project therefrom and take under the inner face of the keeper, as shown. As before stated, the dogs which I place in this 40 hollow bolt are ordinary lock mechanism, and other ordinary lock mechanism which will throw projections from the edge of the bolt may be substituted therefor without departing from the nature of my invention.

45 The construction hereinbefore described can be made by pivoting the dogs directly to the

lock-plate B. A convenient form of construction is to make the bolt E of sheet metal, bent as shown most clearly in Fig. 2, with one arm long enough to form the plate e . The dogs 55 can be pivoted to said plate entirely independent of the lock-plate B, and the bolt, dogs, and springs properly fitted and completed. This complete locking mechanism may be secured to the lock-plate B by merely passing 60 the bolt through the proper hole in the face-plate A and securing the plate e to the plate B by means of one or more rivets, g .

By the foregoing construction I produce a self-locking lock in which the ends of the dogs 65 are completely protected from any bending or wrenching strain either in entering the keeper in closing the lid or afterward, because such strain is received by the stationary hollow bolt E. The bolt also cuts off access to the spring- 70 dogs of a picking-tool inserted between the face-plate and the keeper.

I am aware that a prior patent, No. 48,209, shows a lock having spring-dogs housed in a hollow bolt or slide, said slide having a toothed 75 rack, so that it could be thrown out and in by means of a pinion-shaped key, and the dogs having inclines or cams, which are acted upon by a moving part to force the dogs inward as the bolt is thrown into and out of the lock- 80 case, and I hereby disclaim the same. My lock differs from this prior lock by being self-locking, by having the lock mechanism operated by direct action of the key upon the spring-dogs themselves, instead of upon the bolt in 85 which they are housed, and also operated independent of any movement of the bolt; also, in the fact that the stationary bolt of my lock enters the keeper and protects the spring-dogs during the closing of the desk or box lid, while 90 in the lock disclaimed the spring-dogs are unprotected while entering the keeper, and the hollow bolt or slide does not enter the keeper until after the box or desk lid has been closed and a proper key applied to throw said bolt; 95 and, further, in the fact that the spring-dogs of said prior lock would be inoperative if pivoted to the hollow bolt, as specified in my second claim.

I claim as my invention—

1. The combination of the stationary hollow bolt and inclosed spring-pressed locking mech-

anism adapted to be operated by a key applied directly thereto, and having projections for projecting from the edges of said bolt, which are thrown outward in locking by means of the 5 springs, substantially as described, and for the purpose specified.

2. A lock consisting of the stationary hollow bolt having the plate *e*, formed by an extension of one of its sides, the locking mechanism secured to said plate *e*, the face-plate, and lock-plate *B*, with the plate *e* secured to said plate

B, substantially as described, and for the purpose specified.

3. A self-locking lock having a stationary hollow bolt projecting from the face-plate, and the locking mechanism partially inclosed within said projecting end, substantially as described, and for the purpose specified.

FRANK W. MIX.
